CLAIM

The ornamental design for a flow control apparatus, as shown and described.

DESCRIPTION

FIG. 1 is a side perspective view of a flow control apparatus in accordance with our design, as viewed from a top front corner thereof;

FIG. 2 is a front elevation view thereof;

FIG. 3 is a rear elevation view thereof;

FIG. 4 is a bottom plan view thereof;

FIG. 5 is a top plan view thereof;

FIG. 6 is a side elevation view of the right side thereof; and,
FIG. 7 is a side elevation view of the left side thereof.

The broken lines shown in the figures depict environmental
subject matter and form no part of the claimed design.

1 Claim, 5 Drawing Sheets
